DESK FILE SORTER

Jack Fairchild Fleming, Boonton, N.J., assignor to Sterling Plastics Co., Mountainside, N.J.

Filed Sept. 11, 1969, Ser. No. 19,100

Term of patent 7 years

Int. Cl. D19—99

U.S. Cl. D74—2

FIG. 1

FIG. 2

FIG. 1 is a perspective view of a desk file sorter embodying my new design; and

FIG. 2 is an elevational view of one side thereof, the opposite side being similar in appearance.

The characteristic feature of my design resides in the combination in the desk file sorter disclosed of the base having tapered sides and dividing ribs, together with curved wire dividers, substantially as shown.

I claim:

The ornamental design for a desk file sorter, substantially as shown and described.
